HENRY J. WIEGAND, OF MILWAUKEE, WISCONSIN, ASSIGNOR TO THE CUTLER-HAMMER MFG. CO., OF MILWAUKEE, WISCONSIN, A CORPORATION OF WISCONSIN.

RESISTANCE-CONTROL APPARATUS.

Application filed July 18, 1923. Serial No. 652,462.

This invention relates to resistance control apparatus and while not limited thereto is particularly applicable in conjunction with a suitable capacitance device or devices, as in controlling the current leakage of audion valves or the like.

In such apparatus, wherein sensitive adjustment is very essential, it is necessary that the same be of absolute reliability, smooth and substantially noiseless in operation and capable of critical adjustment.

The present invention has as an object that of providing resistance control apparatus for such and similar purposes exhibiting the foregoing characteristics.

Another object is that of providing resistance control apparatus particularly applicable in controlling the current leakage and consequent potential of certain units of an audion valve or the like, comprising simple and durable parts, compactly and conveniently arranged.

Another object is that of providing a resistance control device wherein provision is made for readily mounting the same with reference to a suitable panel or other support and also with reference to associated instrumentalities.

Another object is that of providing a resistance control device which provides ease and convenience of installation and reliability of operation.

Other objects and advantages will herein-after appear.

In the accompanying drawing wherein is illustrated an embodiment which the invention may assume in practice;

Figure 1 is a side elevational view, partly in section thereof, while;

Fig. 2 is a rear elevational view of the same.

Referring to the drawing and particularly to Fig. 1, the same illustrates a resistance control device comprising a supporting plate 5 of suitable insulating material to be secured to a mounting plate or panel 6 by securing means such as bolt 7.

A resistance element 8 is carried by supporting plate 5, said resistance element preferably comprising a disc 9 of suitable insulating material, having the periphery thereof coated with a relatively narrow band of graphite 10 or other suitable conductive ma-

terial. A saw cut or gap 11 (Fig. 2) is adapted to break the continuity of the conductive coating.

Disc 9 is mounted upon a hub member 12 the latter being provided with an annular flange 13 against which the disc 9 is swaged, spun or otherwise rigidly held. A passage 14, preferably located adjacent said saw cut or the like serves to connect the periphery of the disc 9 with an annular recess 15, the axial depth of said recess being preferably less than the diameter of the passage 14. A connector 16 of relatively soft conducting material such for example as fuse wire, and preferably of a diameter greater than the axial depth of recess 15 is inserted in the passage 14 and wrapped about hub member 12 within said recess 15, the arrangement being such that a portion of connector 16 will project axially beyond the face of disc 9, said portion being forced and held against and in permanent electrical engagement with flange 13 during the mounting of the disc 9 and hub member 12 by swaging or otherwise as aforescribed. The other terminal portion of said connector is preferably arranged to terminate substantially flush with the periphery of the disc 9, being preferably flattened and expanded somewhat to insure permanent and adequate contact with the graphite 10 on the periphery of the disc.

Hub member 12 is provided with reduced terminal portions 17 and 18 having shoulders 19 and 20 associated therewith respectively. The hub terminal portion 17 is adapted to be inserted within a suitable opening in supporting plate 5 to terminate substantially flush with the outer surface of the latter. A washer 21 is preferably interposed between said disc and said supporting plate to provide for unhampered angular movement of the former relative to the latter, said washer being strung upon the reduced terminal portion 17 of the hub 12 to abut the shoulder 19.

A combined center terminal and supporting member 22 preferably composed of resilient metal such as phosphor bronze is secured to the supporting plate 5 as by screw bolts 23. Said member 22 is provided with an off-set portion 24 having an aperture 25 to receive and provide a bearing for the

reduced portion 18 of hub member 12. In assembling the disc 9 with respect to supporting plate 5 the off-set portion 24 is sprung outwardly to permit insertion of the 5 reduced portion 17 of hub member 12 within the aperture 26 in supporting plate 5, the washer 21 serving as a bearing plate and spacer between the face of disc 9 and the supporting plate 5. Thereafter said off-set 10 portion 24 is permitted to spring back to normal position abutting the shoulder 20 of the hub, the reduced portion 18 being journaled in aperture 25, said resilient member 22 thus serving to maintain the parts in as- 15 sembled relation while providing for ready removal, replacement or substitution of the disc. Said hub 12 is further provided with internal screw threads to receive a screw 27, the head of said screw being adapted to lock 20 against the adjacent face of the reduced portion 18 of said hub for positively anchoring the screw to said hub and disc. Said screw is further adapted to penetrate the supporting plate 5 and the panel 6, assuming 25 the device to be panel mounted, and to receive therebeyond a suitable operating knob 28 which is locked to said screw in suitably spaced relation to the stationary parts in any desired or preferred manner, as by means 30 of lock nut 29.

A stud 30 having a pedestal portion 31 and a screw portion 32 is riveted to the supporting plate 5, said pedestal portion having a through passage 33 to receive a brush 34 35 of graphite or other suitable material, said brush being arranged to make contact with the periphery of disc 9. A spring clip 35 of resilient material is held in place by a nut 36 acting on screw portion 32 of said 40 stud. Said clip is adapted to exert pressure on brush 34 thereby keeping the same in positive contact with the disc.

Upon rotation of the disc, by means of its operating knob aforescribed, said 45 brush is adapted to deposit upon the periphery of the disc the aforementioned thin conductive coating comprising material of the brush. Also the relative movement of the disc and brush incident to service is sufficient to restore and maintain the coating 50 against loss by abrasion or otherwise. In practice the periphery of the disc is preferably rounded or tapered axially, substantially as illustrated whereas the co-operating portion of the brush may be preformed 55 to a complementary shape or in any event will speedily assume such a shape in service. This feature is of importance in that substantially a spherical contact surface of 60 maximum area is provided and an adequate contact of minimized resistance is insured.

If desired the periphery of the disc may be slightly roughened to facilitate reception and retention of the conductive coating, al- 65 though ordinarily such expedient is not nec-

essary or even desirable. Also it should be understood that the periphery of the disc may be pre-coated with conductive material either similar or dissimilar to that of the brush.

70

The supporting member 22 is preferably extended beyond the region of attachment thereof to the supporting plate 5 and reflexed to provide, either directly or indirectly, a terminal support for one end of a 75 suitable condenser or the like to be employed in conjunction with the resistance control apparatus aforescribed.

75

The opposite end of such condenser or the like is preferably mechanically supported by 80 and in electrical contact with the screw portion 32 of stud 30, said stud being preferably prolonged to provide a suitable joint terminal for such condenser and resistance control device.

85

In practice the first mentioned end of the condenser may be connected, as by a terminal stud, directly to the adjacent reflexed end of the supporting member 22, thereby obviously connecting the condenser and resistance control device electrically in the usual parallel relation to one another. However, preferably a slotted conductive link 37 is interposed between said adjacent ends of the condenser and said supporting member for 90 longitudinal and pivotal adjustability relative to both, thereby adapting the device to practically any desired length or other dimension of the particular condenser or the like to be employed.

95

In Fig. 2 is illustrated an adaptation of the device to mounting in a relation of support solely by means of a single conductive terminal, such for example as the grid terminal 38 of an audion tube socket. Thus a 100 flexible jumper 39 may be mechanically anchored and electrically connected to the device as shown in Fig. 1, the free end of said jumper having an opening 40 to receive a suitable supporting terminal such as the 105 terminal 38 of the tube socket 41, the entire device being held in place by thumb nut 42. This method of mounting provides a very short lead to the grid of the audion valve 110 thereby minimizing external influence upon the grid.

110

When the device is arranged for panel mounting as shown in Fig. 1 the circuit may be traced from terminal 43 through the capacitance device 44 to terminal 45 and 120 also in parallel with the former circuit from terminal 43 and pedestal portion 31, through brush 34 to that portion of the graphite coating on the periphery of disc 9 determined by the adjustable setting of same, 125 through connector 16 to hub 12, through resilient member 22 and conductive link 37 to terminal 45. As shown in Fig. 2 the circuit will be identical with the aforescribed with the exception that flexible 130

jumper 39 will function as a terminal in place of terminal 45.

What I claim as new and desire to secure by Letters Patent is:

- 5 1. In resistance control apparatus, in combination, a circular element having the periphery thereof coated with graphite, the periphery of said element being cut away at a given region to provide for interruption of said coating, a spring tensioned graphite brush to coact with the peripheral portion of said element for maintaining the coating of graphite thereon, and a rotatable shaft secured to said element to effect operation thereof.
- 10 2. In resistance control apparatus, the combination with a circular element having a peripheral portion thereof coated with conductive material, said element having a centrally located depression connected with the periphery thereof by a passage, of a soft metallic connector located in said passage and having a portion located within said depression and another portion electrically connected with said conductive coating and a conductive hub member rigidly secured to said circular element in a relation to maintain contact with said connector.
- 15 3. In resistance control apparatus, the combination with a circular element having a peripheral portion thereof coated with conductive material, said conductive coating having its continuity interrupted at a given region, said element having a centrally located annular depression connected with the periphery of the same by a passage adjacent the break in the continuity of said conductive coating, of a soft metallic connector located in said passage and having a portion located within said annular depression and another portion electrically connected with said conductive coating and a hub member rigidly secured to said circular element in a relation to maintain contact with said connector.
- 20 4. In resistance control apparatus, the combination with a circular element having a peripheral portion thereof coated with conductive material said conductive coating having its continuity interrupted at a given region, said element having a centrally located annular depression connected with the periphery thereof by a passage adjacent the break in the continuity of said conductive coating, of a soft metallic connector located in said passage and having a portion coiled within said annular depression and another portion electrically connected with said conductive coating, the axial depth of said depression being less than the axial extent of the coiled portion of said connector, a conductive hub to be rigidly secured to said circular element and within the coiled portion of said connector, said hub having a flange to engage the coiled portion of said connector, and said hub and said circular
- 25 element having associated parts to maintain positive compression contact between said connector and said flange.
- 30 5. In a resistance control apparatus, the combination with a circular insulator, a resistor carried thereby and a central hub for said insulator, said hub having parts to project axially upon opposite sides of said insulator, of a support therefor comprising an insulating base having an off-set bracket secured thereto to receive said insulator between said base and said bracket, said base and bracket having aligned openings to receive the projecting portions of said hub, said bracket comprising resilient material to provide axial pressure upon said insulator and hub.
- 35 6. In resistance control apparatus, the combination with a circular insulator having the periphery thereof coated with conductive material, the periphery of said insulator being interrupted at a given region, a conductive hub centrally located in said insulator, a rotatable operating shaft secured to said hub, a soft metallic connector electrically connecting the peripheral conductive material with said hub member and a clamping support for said insulator comprising a resilient conductive bracket to engage and provide a terminal of said hub member.
- 40 7. The combination with an insulating base, a resilient conductive clamping bracket secured thereto, a resistance element to be inserted and retained between said base and said bracket, and means to electrically connect the resistor of said resistance element with said bracket, of a terminal support carried by said bracket for securing and electrical connection of an associated control instrumentality.
- 45 8. The combination with an insulating base, a resilient conductive clamping bracket secured thereto, a resistance element to be inserted and retained between said base and said bracket and means to electrically connect the resistor of said resistance element with said bracket, of a co-operating contactor for said resistance element, a conductive contactor support carried by said base, and auxiliary supporting terminals carried by said support and said bracket.
- 50 9. The combination with an insulating base, a resilient conductive clamping bracket secured thereto, a resistance element to be inserted and retained between said base and said bracket and means to electrically connect the resistor of said resistance element with said bracket, of a co-operating contactor for said resistance element, a conductive contactor support carried by said base and terminals carried by said support and said bracket to provide for mechanical securing and electrical connection of an associated control instrumentality.
- 55 10. The combination with an insulating

- base, a resilient conductive clamping bracket secured thereto, a resistance element to be inserted and retained between said base and said bracket and means to electrically connect the 5 resistor of said resistance element with said bracket, of a co-operating contactor for said resistance element, a conductive contactor support carried by said base and relatively adjustable, terminals carried by said support and said bracket to provide for mechanical 10 securing and electrical connection of an associated control instrumentality.
11. The combination with an insulating base, a resilient conductive clamping bracket 15 secured thereto, a resistance element to be inserted and retained between said base and said bracket and means to electrically connect the resistor of said resistance element with said bracket, of a co-operating contactor 20 for said resistance element, a conductive contactor support carried by said base, terminals carried by said support and said bracket to provide for mechanical securing and electrical connection of an associated control instrumentality, and means comprising a pivotally and slidably adjustable slotted link to 25 secure certain of said terminals to its associated support.
12. The combination with an insulating base, a resilient conductive clamping bracket 30 secured thereto, a resistance element to be inserted and retained between said base and said bracket and means to electrically connect the resistor of said resistance element with said bracket, of a co-operating contactor for said resistance element, a conductive contactor support carried by said base, terminals carried by said support and said bracket to provide for mechanical securing and electrical connection of an associated control instrumentality, and means comprising a pivotally and slidably adjustable slotted link to secure certain of said terminals to its associated support.
13. The combination with an insulating base, a resilient conductive clamping bracket secured thereto, a resistance element to be inserted and retained between said base and said bracket and means to electrically connect the resistor of said resistance element with said bracket, of a co-operating contactor for said resistance element, a conductive contactor support carried by said base, auxiliary supporting terminals carried by said support and said bracket, and a conductive supporting element secured to said base in contact with said bracket.

In witness whereof I have hereunto subscribed my name.

HENRY J. WIEGAND.
